SELECTOR BANK FOR AUTOMATIC
TELEPHONE SYSTEMS

Hubert Harvey, Chatswood, near Sydney, New South Wales, Australia, assignor to Telephone & Electrical Industries Pty. Limited, Redfern, near Sydney, a company incorporated in the State of New South Wales, Australia

Application February 20, 1948, Serial No. 9,743
In Australia February 24, 1947

5 Claims. (Cl. 175—306)

1

This invention relates to selector banks, either of the bimotional type or of the uniselector type, which are intended to be mounted in sets in the shelves of automatic telephone equipment.

Construction of selector banks of the bimotional type as now adopted in modern equipment, is carried out in two operations. It is usual in the first operation to apply a plurality of contacts radially to an arcuate strip of adhesive insulating cloth, the reverse side of which is applied to an arcuate strip of insulating board. These arcuate strips with the contacts adhering thereto are then, in the second operation, assembled with arcuate insulating separators between them to form "levels" each of which is separated from its adjoining "level" by a screening plate usually of aluminium.

Usually there are ten "levels" in each bank of the bimotional type, and as the construction at present adopted involves several layers of components in each "level", the total number of layers in each bank, including the aforesaid screening plates, in seventy-nine.

For efficient service it is essential that these banks when assembled should conform fairly rigidly to stipulated dimensions and, in practice, any departure from prescribed tolerances results in banks being rejected by authorities responsible for installation of telephone equipment.

It will be appreciated that with the multiplicity of layers now adopted, any slight variation in the thickness of the respective layers can have an accumulative effect which would place the bank beyond the prescribed tolerance.

The present invention has been devised primarily with the object of facilitating assembly of the selector banks and simplifying their construction.

The invention results in substantial reduction in the number of layers involved in construction of the banks, with consequent material reduction in the extent of departure from stipulated dimensions.

According to the present invention the contacts as ordinarily employed are assembled in radially disposed grooves formed in an arcuate separator of moulded plastic material having good insulating properties and high dimensional stability. Polystyrene is one appropriate material for this purpose. The grooves are accurately formed in the process of moulding, and serve to hold the contacts in their correct location while the bank is being assembled. The grooves are of such depth that the outer faces of

2

the contacts lie substantially flush with the surface of the plastic separator. The faces of such contacts may, however, protrude sufficiently to ensure rigid clamping of the contacts when the several plastic separators, with intervening insulating separators and screen segments hereinafter referred to, are assembled and secured together to constitute the bank.

In order however, that the invention may be fully understood and readily carried into practical effect, reference is now made to the drawings accompanying and forming part of this complete specification.

Figure 1 is a plan of a bimotional selector bank embodying the present invention;

Figure 2 is a plan of one of the aforesaid plastic separators as utilized in the bank illustrated by Figure 1;

Figure 3 illustrates section of the plastic separator as indicated by the line 3—3 in Figure 2, on an enlarged scale;

Figure 4 is an expanded sectional view indicating, schematically, portion of a selector bank embodying the present invention; and

Figure 5 is an enlarged elevation looking in the direction of the arrow in Figure 1 of one end of the bank there illustrated, some, only, of the levels being indicated in full lines in this instance.

30 In construction of the selector bank illustrated, each "level" indicated by L in Figures 4 and 5 comprises two of the plastic separators 10 as shown by Figure 2, and an intervening insulating separator 11. One face of each of the separators 10 (which would be the undersurface in Figure 2) is quite plain, whilst the other face has accurately formed in it a plurality of grooves 12 to receive contacts 13. These contacts fit closely within the grooves 12, and as will be observed on reference to Figure 4, the contacts 13 lie substantially flush with the face of the separator in which they are set. The two separators 10 of each "level" with contacts 13 so arranged in them are disposed face to face as indicated in Figure 4, with the intervening insulating separator 11 between them. It will be noted that each of the grooves 12 in the separators 10 has an angularly disposed portion 14, so that when the several separators are assembled the terminal portions of the contacts 13 projecting beyond one of the separators 10 will project at an angle in relation to those projecting from the other separator 10 of the same "level," as will be apparent on reference to Figure 1.

40

45

50

The insulating separators 11 may be of phenol fibre or any other appropriate insulating material, but preferably they are of a paper base.

Between each of the "levels" L there is a relatively thin screening segment 15 which preferably is of copper foil. These segments 15 have integral tags such as 16 (see Figure 5) which are arranged to project alternatively at each end of the bank and are folded in to make electrical contact with the relative end of the next succeeding segment 15 in accordance with existing practice.

Ten of the "levels" L together with screening segments 15 are assembled as explained, and these are clamped between upper and lower plates 17, preferably of steel, the whole being secured together as by screws 18 (Figure 1).

The foregoing construction and arrangement of the several components materially reduces the total number of layers in the bank. Moreover the great reduction in the total number of components adopted, materially reduces time absorbed in assembling the bank and in the subsequent maintenance thereof; and it will be appreciated that with the smaller number of components, the cumulative effect of incidental departures from prescribed measurements of the individual components will be considerably less than in banks constructed in accordance with existing practice. In some instances the contacts 13 may be set in the separators 10 during the process of moulding.

Whilst the invention has been described more particularly with regard to banks of the bimotional type, it will be understood that the mode of construction may be applied with equally satisfactory results to banks of the uni-selector type.

I claim:

1. A selector bank, for use in automatic telephone equipment comprising a plurality of "levels" each of which consists in a pair of arcuate insulating plastic separators, an intervening insulating separator, and a plurality of contacts rigidly held between said plastic separators and said insulating separator, the opposed faces of said arcuate plastic separators having shallow, accurately defined grooves therein, and said contacts being accommodated in said grooves, and lying substantially flush with the inner faces of the arcuate plastic separators.

2. A selector bank, for use in automatic telephone equipment, comprising a plurality of "levels" each of which consists in a pair of arcuate insulating plastic separators, an intervening insulating separator, and a plurality of contacts, the opposed faces of said arcuate plastic separators having accurately defined shallow grooves therein and said contacts being rigidly held in said grooves and having their respective outer faces substantially flush with the opposed portions of the faces of said arcuate plastic separators between the grooves and being so disposed that the terminal portion of those contacts in one of said arcuate plastic separators projects at an angle with respect to the terminal portion of those contacts in the other of said arcuate plastic separators, and a screening member interposed between each of said "levels" of said selector bank.

3. A selector contact bank for use in automatic telephone equipment comprising a plurality of superimposed contact levels each consisting in

a pair of insulating plates of arcuate plan and uniform thickness, an insulating plate between and separating said arcuate plates, said intervening plate being arcuate in plan and having a radial extent greater than said first mentioned plates, the opposed faces of said arcuate plates having accurately defined substantially radially extending grooves provided therein, each groove having a planar base surface and the portion of the face of each plate between the respective grooves therein being a planar surface, and a plurality of similarly formed contacts having opposite planar surfaces and a thickness substantially equal to the depth of said grooves and disposed in said grooves with one planar face contacting the planar base surface of the grooves and the opposite outer planar face of each contact being disposed substantially flush with the adjacent planar base portions of the said arcuate plates.

4. A selector contact bank comprising a plurality of superimposed contact levels each consisting in a pair of similarly formed insulating plates arcuate in plan and having uniform thickness, an insulating plate between and separating the said arcuate plates, each of said arcuate plates having a plurality of spaced, radially extending grooves accurately defined therein, each groove having a planar base surface and including an angular extending portion adjacent the longer perimetrical edge of said plate, a plurality of similarly formed contact members of uniform thickness substantially the same as the depth of said grooves and each having an angularly extending terminal portion, the plates being disposed in opposed relation with the grooved sides thereof facing one another on opposite sides of said separator plate and the said contacts being respectively disposed in said grooves and rigidly held between the arcuate plates and the separator plate with the terminal portions of the contacts disposed in the grooves of one plate extending at an angle with respect to the terminal portion of the contacts in the grooves in the other plate and the inner surface of each contact contacting the base of each groove and filling the same and the outer surface of each contact being flush with the adjacent face portion of each plate between the respective grooves therein and each outer face of each contact being against the adjacent portion of the separator plate.

5. A selector contact bank as defined in and by claim 4, and a screening member interposed between each of said levels.
